COMPOSITE ANODE FOR X-RAY TUBES

Filed Sept. 19, 1925

FIG. I

FIG. 2

UNITED STATES PATENT OFFICE.

CLAYTON TRIDLE ULREY, OF EAST ORANGE, AND LOUIS F. EHRKE, OF NEWARK,
NEW JERSEY, ASSIGNEES TO WESTINGHOUSE LAMP COMPANY, A CORPORATION
OF PENNSYLVANIA.

COMPOSITE ANODE FOR X-RAY TUBES.

Application filed September 19, 1925. Serial No. 57,271.

This invention relates to X-ray tubes and more particularly to such tubes adapted for diagnostic purposes.

The present invention is an improvement 5 upon the X-ray tube shown in co-pending application, Serial No. 38,395, filed June 20, 1925, assigned to the present assignee and to the X-ray tubes disclosed by the other applications referred to in said co-pending application.

Our invention and improvement relates to the provision in an X-ray tube of the type disclosed in said co-pending applications of means for external cooling and more specifically to the construction of the anode unit for securing good heat conduction whereby a greater energy input may be utilized with advantageous results.

In view of the foregoing it is an object of 20 the present invention to provide an X-ray tube of the type disclosed in said co-pending application with external cooling means.

Another object of the invention is to provide an anode construction enabling the expeditious assembly and sealing thereof in the envelope or container of an X-ray tube.

A further and more specific object of our 30 invention is to provide an anode consisting of a plurality of parts certain of which are of different metals and which are so united and assembled that good heat conduction is obtained from the target end of the anode to the other or radiator end.

Other objects of the invention will be apparent as the following description of the invention is read.

A better understanding of the invention may be obtained by referring to the accompanying drawing in which:

Fig. 1 is a cross-sectional view of an X-ray tube embodying the invention and

Fig. 2 is a detailed view of the anode assembly.

Referring to Fig. 1 of the drawing an X-ray tube embodying our invention may comprise a glass envelope 3 of cylindrical shape to which is sealed at 4 a reentrant tube 5 which has its end 6 extending in close proximity to the end 7 of the container or envelope 3. Enclosing the end 6 of the reentrant tube 5 and supported thereby is an inverted cup-shaped metallic screen member 8, said member having a relatively small opening 9 in the end

wall 11 thereof. The end 6 of the reentrant tube supports a cup-shaped body 12 of insulating material by means of an outwardly projecting flange 13 integral with said body. The body 12 has wall 14 having small circular opening 15 therein, said opening being in line with the longitudinal axis of the X-ray tube. Disposed within the insulating body 12 is a filament or electron-emitting cathode 16 bent in the form of a spiral having a centrally disposed opening 17 which opening is also in axial alignment with the longitudinal axis of the X-ray tube. The ends 18 and 19 of the filamentary cathode pass through apertures 21 and 22, respectively, in a mica disk 23 and through opening 24 and 25, respectively, in the wall 11 of the metallic member or screen 18. The mica disk 23 has a central opening 26 therethrough also in axial alignment with the longitudinal axis of the tube.

The ends 18 and 19 of the filamentary cathode are welded or otherwise secured to 75 leading-in wires 27 and 28, respectively, said wires being hermetically sealed in the glass walls of the envelope 3 or else in presses 29 and 31 of stems 32 and 33 fused to the walls of the envelope 3. The leading-in wires 27 and 28 may be secured to contact caps 27' and 28' respectively.

The above described structure is fully disclosed and claimed in the co-pending applications referred to heretofore and forms no 85 part of the present invention except where claimed in combination with features subsequently to be disclosed.

The present invention, as stated heretofore, relates more particularly to constructing the 90 anode in such manner as to provide for external cooling and also to simplify as well as to reduce the cost of assembly of the component parts of the tube.

The anode as a whole is designated by the 95 numeral 34 and comprises essentially three parts, namely, the target portion 35, the seal portion 36 and the radiator portion 37.

The target portion 35 consists of a solid rod or copper or other good heating-conducting 100 material which has a head portion 38 having a rounded end 39 in which is secured by threading or otherwise a target 41 of good ray-radiating material, such as thorium and the like. A reduced shank 42 extends from 105 the head portion, said shank having a

threaded section 43, for a purpose later to be described and a threaded end 44 for securing the target portion 35 to the seal portion 36.

The seal portion 36 may consist of a rod 5 of copper having a threaded aperture or recess 46 in one end for receiving the threaded end 44 of the target portion and an enlarged portion at the opposite end which also has a threaded recess for securing the seal portion 10 to the radiator portion 37. The enlarged portion 47 has an annular flange 49 extending therefrom, said flange being sufficiently thin so that it will stretch and will not exert such a pressure upon the glass as to shear or break 15 the same. A thickness of from .008 to .012 inches has proven satisfactory. It is well known that copper or its oxide will wet glass as to form an hermetic seal therewith.

The radiator portion 37 comprises a shank 20 51 of aluminum having a threaded end 52 for engaging the threaded recess 48 and having the other end 53 reduced in cross-section. A brass sleeve 54 is forced over the reduced end 53 of the shank and supports a plurality of 25 radiating vanes or fins 55 of disk-shape spaced apart by washers 56 which latter are clamped to brass sleeve 54 between flanges 57 integral with the latter. The end 58 of the brass sleeve 54 engages a shoulder 59 on the shank 30 51. A washer 61 and screw 62 may be employed to more firmly secure the radiator on the shank. The radiator portion 37 may, if desired, be cast in one piece and be made of aluminum.

35 The advantages secured by constructing the anode in three parts are as follows:

It is desirable to make the seal portion 36 as a separate unit as it prevents injury through oxidation of the target since in sealing the seal portion 36 to glass it is necessary to heat the copper to a high temperature. Where the target portion is separate at the time such operation is performed, the heat thus necessary to affect the sealing can not 40 reach the target inasmuch as such operation can be made while the two parts are separated. It is also advantageous to make the seal portion separate from the standpoint of economy, since in the event of a faulty or 45 damaged seal the main part of the target is not lost. In addition the seals may be made separately and tested before assembling the parts of the anode.

It is of advantage to make the radiator portion 50 55 separate from the seal portion in order to facilitate the construction and to save material and labor in case of a faulty or damaged seal.

The heat conduction from the target to the 60 radiator during operation of an X-ray tube embodying the present anode construction is not materially impaired by such construction as the threaded unions between the parts are so constructed that the thermal contact improves with rise in temperature. As will

be readily appreciated from an inspection of the anode construction as the target portion becomes heated through electronic impact upon the target 41, the copper rod 42 expands and since the heat is flowing from this portion toward the radiator it is obvious that said portion will be at a more elevated temperature than the seal portion 36, owing to this difference in temperature and the disposition of the end of 44 of the target portion in the recess 46 of the seal portion it is obvious that the threaded end of the rod will expand into firm contact with the threads of the recess 46, thus providing for good heat conduction through this connection.

Conduction of the heat between the seal portion 36 and the radiator portion 37 is facilitated by making the portion 51 of the latter of aluminum. Owing to aluminum having a greater coefficient of expansion than 85 that of copper of which the seal portion is made, it is obvious that contact between the threaded end 52 and threaded recess 48 improves as the temperature rises. A further advantage in the use of aluminum is that on 90 account of its low density the stress on the seals, due to the weight of the radiator, is considerably less than if copper or a heavier metal were used.

The anode 34 may be supported within the 95 envelope by means of a sleeve 63 of metal which may have an interiorly threaded collar 64 integral therewith for connection to the threaded portion 43 on the target portion 35. The sleeve 63 is of such size as to frictionally 100 engage the inner surface of the reentrant tube 5, and may be provided with longitudinal and transverse slots 65 and 66 to allow for expansion and contraction and to avoid placing too much strain upon the reentrant tube.

The seal portion 36 through the thin annular flange 49 may be hermetically sealed at 67 to a flare 68 which in turn may be fused to the envelope 3 at 69.

As set forth more fully in the co-pending 110 application above identified, the tube may be evacuated in any suitable manner and thereafter mercury vapor or an inert gas admitted thereto at about one micron pressure. In addition the spacing of the electrodes with respect to each other and the distance between the anode and inner wall of the reentrant tube 5 should be such that no appreciable gaseous 115 ionization occurs. The functions of the various parts of the device except the anode structure and the manner in which the same operates is more fully set forth in the co-pending applications heretofore referred to and inasmuch as these form no part of the present invention no detailed explanation is essential 125 to a full understanding thereof. It will also be noted that by reason of the construction described X-rays generated are taken out of the tube along its longitudinal axis.

Modifications of the invention will occur 130

to those skilled in the art, however such modifications are contemplated as come within the spirit and scope of the invention as defined by the appended claims.

5. What is claimed is:

1. An anode for an X-ray tube of the character described comprising a target portion, a seal portion removably secured to said target portion, and a radiator portion, said seal and target portion being composed of the same material and the former having an opening in which said target portion is fitted.
2. An anode for an X-ray tube of the character described comprising a target portion 15 of copper, a seal portion of copper and a radiator portion of aluminum, said target and radiator portions being secured in said seal portion, and said seal portion having an opening in which said target portion is fitted.
3. An anode for X-ray tubes and the like comprising a rod of copper, a seal portion of copper having a recess for receiving the end of said rod, and a radiator portion of aluminum secured to said seal portion.
4. An anode for an X-ray tube comprising a rod of copper having a target in one end thereof and being threaded at the other end, a seal portion consisting of a threaded recess at one end for receiving the threaded end of said rod, a sealing flange extending from the other end of said seal portion, and an aluminum rod secured in the last-mentioned end of said seal portion, said aluminum rod having a radiator secured thereto.
5. An anode for an X-ray tube comprising three parts, one part consisting of a rod of

copper having a rounded end with a target inserted therein and the other end being threaded, and a threaded portion intermediate the ends of said rod, another part of 40 said anode consisting of a rod of copper having a recess in each end thereof and an annular flange extending from one end, said flange being relatively thin and serving to form a seal with glass, and the third part of 45 said anode consisting of a rod having one end threaded and having a radiator secured to the other end.

6. An X-ray tube comprising an envelope, a reentrant tube therein and fused at one end 50 thereto, an anode housed within said tube, said anode comprising an anode portion having a target in one end thereof and means for supporting said anode upon the inner side of said tube, and a seal portion secured to said 55 anode portion, said seal portion having a flange for hermetically sealing said envelope to said seal portion.

7. An X-ray tube comprising an envelope, a cathode and an anode therein, focusing 60 means adjacent said anode and cathode, said anode comprising a rod of good heat conducting material, a sealing portion threadedly engaging the end of said rod, and a radiator portion threadedly engaging said sealing portion and means on said rod for supporting the same within said envelope.

In testimony whereof, we have hereunto subscribed our names this eighteenth day of September, 1925.

CLAYTON TRIDLE ULREY.
